UNITED STATES PATENT OFFICE.

HENRY I. BENEDICT, OF NEW YORK, N. Y.

PROPELLER.

1,148,434.

Specification of Letters Patent. Patented July 27, 1915.

Application filed October 19, 1914. Serial No. 867,845.

To all whom it may concern:

Be it known that I, HENRY I. BENEDICT, a citizen of the United States, and a resident of the city of New York, borough of Manhattan, in the county and State of New York, have invented a new and Improved Propeller, of which the following is a full, clear, and exact description.

This invention relates to propellers for marine and air crafts and relates more particularly to a propeller of the oscillatory type in contradistinction to rotary propellers.

The invention has for its general objects to improve and simplify the construction of propellers so as to be highly efficient in use, of durable and substantial design and equally effective in both forward and reverse propulsion.

More specifically the object of the invention is the provision of a propeller capable of oscillating laterally or vertically and having in addition to an oscillatory motion a movement of translation while held at such a pitch that its action on the water or air results in a propelling impulse and these impulses are produced in the movement of the propeller in both directions.

A further object of the invention is the provision of actuating means for the propeller whereby a propelling force is produced at all points except at the limits of the oscillatory or reciprocatory movement thereof, when the actuating means passes through its dead centers, which fact, taken in connection with the fish-tail shape of the propeller causes a powerful and practically uniform propelling impulse to be given to the craft on which the propeller is mounted.

With such objects in view, and others which will appear as the description proceeds, the invention comprises various novel features of construction and arrangement of parts which will be set forth with particularity in the following description and claims appended hereto.

In the accompanying drawings, which illustrate certain embodiments of the invention and wherein similar characters of reference indicate corresponding parts in all the views, Figure 1 is a bottom plan view of the stern of a boat equipped with the improved propelling mechanism; Figs. 2, 3, 4 and 5 are views of the propeller and driving means shown in four successive positions occupied during one revolution; Fig. 6 is a perspective

view of the propeller detached; Fig. 7 is a perspective view of the crank shaft for operating the propeller; Fig. 8 is a side view of the crank shaft with the crank pin in section; Fig. 9 is a side view of the steering part of a boat with a modified form of propeller actuating mechanism; and Fig. 10 is a detail view of the eccentrics embodied in the mechanism shown in Fig. 9.

In the present instance the propeller is shown in connection with a boat, but it is to be understood that it can be used with air crafts.

Referring to the drawing, A designates the hull of a boat to which is applied the propeller B. This propeller may be disposed with its plane horizontal or vertical and it is more or less in the shape of a fish's tail. The propeller is adapted to have a motion of translation up and down or to the right or left, according to the disposition of the plane of the propeller, and during the movement of the propeller it is inclined in the same general direction with respect to the length of the boat throughout the range of each stroke, but the inclination during one stroke is opposite to the inclination during the succeeding stroke. In other words, the propeller does not have a swinging movement about its front edge as a center, for instance, but it moves bodily while maintaining a decided pitch, whereby a propelling thrust is exerted on the boat. As the propeller has a bodily movement transversely to the line of propulsion it is movably connected with the hull by means of thrust rods 1 which are hingedly connected at 2 to the front edge of the propeller and which are hingedly connected at 3 with the hull of the boat at a point in front of the propeller. The propeller is adapted to be actuated by a shaft 4 suitably rotated by an engine within the boat, and on this shaft is a crank arm or equivalent means 5 which is provided with a crank pin 6 engaged in a recess 7 provided in the front edge of the propeller, such recess being elongated in a plane coincident with the longitudinal center plane of the propeller. The crank pin is disposed parallel with the crank shaft 4 when viewed in one plane, but in another plane at right-angles to the first-mentioned plane the crank pin is disposed obliquely to the axis of the engine shaft 4. By reason of this arrangement of the crank pin a rotation of the shaft will cause the crank pin to

move back and forth in the recess or slot 7 of the propeller, with a motion somewhat after the fashion of a harmonic motion, but the propeller is at all times disposed at an angle to the axis of the driving shaft, except while the crank pin passes through its dead centers. In Fig. 2 the crank pin 6 is at its upper dead center and as the shaft 4 revolves and with it the crank pin, the latter becomes inclined to the horizontal and reaches its maximum point of inclination at the end of the first quarter of the revolution, as shown in Fig. 3, and during the next quarter of the revolution the angle of inclination gradually changes until the propeller is parallel with the shaft 4, as shown in Fig. 4, where the crank pin is at its lower dead center. As the shaft continues to revolve the crank pin ascends and gradually changes its inclination, so that it reaches the position shown in Fig. 5 at a point midway between the upward travel of the crank pin, and during the fourth quarter of the revolution of the crank pin it changes its inclination from the position shown in Fig. 5 to that shown in Fig. 2. It will be noted that the angle of inclination during the first half of the revolution from Fig. 2 is opposite to the angle of inclination during the second half from Fig. 4 to Fig. 2. As the propeller B is inclined at all points except when the crank is at its upper or lower dead center the propeller will have a pitch which results in a powerful thrust being exerted, due to the action of the propeller on the water, and this thrust is the same both in the up and down stroke of the propeller. Obviously the direction of propulsion depends upon the direction in which the shaft 4 is rotated, and therefore when it is desired to reverse the direction of propulsion it is merely necessary to reverse the direction of rotation of the shaft. When the propeller is moving downwardly its under surface will act on the water and produce the propelling force, while on the up stroke of the propeller the upper side acts on the water to produce the propelling force. During the up and down strokes of the propeller the bars 1 swing on their front ends as centers, since these bars are pivotally connected with the propeller and the thrust produced by the propeller is transmitted through these bars to the boat.

To reduce friction to a minimum the crank pin 6 may include a roller or other anti-friction device 8 which is disposed in the chamber of the propeller, whereby a rolling contact is provided as the crank pin moves back and forth.

Instead of employing the crank pin construction hereinbefore described the propeller B can be actuated by means shown in Fig. 9. This propeller is connected with a pair of devices which cause the propeller to

move back and forth while maintaining the same at an inclination to the line of propulsion. The inclination or pitch of course changes alternately as the strokes change. In the present instance the front and rear portions of the propeller are connected by freely laterally movable links or equivalent devices 9 and 10 with eccentric straps 9^a and 10^a which surround eccentrics 9^b and 10^b, both of which latter are fastened to an engine shaft 11. The eccentrics are preferably angularly displaced one from the other as shown in Fig. 10, so that the angle of inclination of the propeller will gradually change from zero at the beginning of a stroke to maximum at mid stroke, and zero at the end of the stroke, and thereafter pass through the same cycle with an opposite inclination on the next stroke. With this arrangement the direction of movement of the propeller can be reversed by merely reversing the rotation of the shaft 11 for the forward or backward propulsion of the boat.

While the propeller and operating mechanism has been shown in connection with a shaft driven from an engine within the boat it is to be understood that the invention can be used in connection with an outboard driving motor applied to the stern of a boat.

From the foregoing description taken in connection with the accompanying drawings, the advantages of the construction and method of operation will be readily understood by those skilled in the art to which the invention appertains, and while I have described the principle of operation together with the apparatus which I now consider to be the best embodiment thereof, I desire to have it understood that the apparatus shown is merely illustrative and that such changes may be made when desired as are within the scope of the appended claims.

Having thus described my invention, I claim as new and desire to secure by Letters Patent:

1. The combination of a craft to be propelled, with a propeller movable back and forth at approximately right-angles to the line of propulsion, a rotary shaft extending longitudinally of the craft, a single means between the shaft and propeller for moving the latter back and forth and alternately changing the pitch of the propeller synchronously with the strokes thereof, and a device hingedly connected with the propeller and movably connected with the craft, whereby the thrusts from the propeller are transmitted to the craft.

2. The combination of a craft to be propelled, a fish-tail-like propeller, a driving shaft, a crank pin on the shaft arranged at an angle to the axis thereof, said propeller having means with which the crank pin engages to cause the propeller to move back

and forth while disposed at an angle to the said shaft, and means for connecting the propeller with the craft to propel the same.

3. The combination of a craft to be propelled, a fish-tail-like propeller having a recess in its front portion and at the center, a shaft disposed in front of the propeller, a crank pin on the shaft disposed at an angle to the axis of the shaft and engaging in the recess of the propeller to reciprocate and alternately change the pitch of the propeller, and means for connecting the propeller with the said craft to propel the same.

4. The combination of a craft to be propelled, a flat propeller oscillatory in only a single plane, a crank pin adapted to revolve about an axis transverse to the plane of mo-

tion of the propeller, and the crank pin being disposed at an angle to such axis, and means carried by the propeller with which 20 the crank pin engages for vibrating the propeller and alternately changing the pitch of the propeller as the strokes thereof change, and a mechanical connection between the propeller and craft whereby the thrust of 25 the propeller propels the craft, both halves of the propeller being in the same plane.

In testimony whereof I have signed my name to this specification in the presence of two subscribing witnesses.

HENRY I. BENEDICT.
